UNITED STATES PATENT OFFICE.

RICHARD LUKINS, OF RANDOLPH, NEBRASKA.

CAR-PUSHING MACHINE.

SPECIFICATION forming part of Letters Patent No. 376,670, dated January 17, 1888.

Application filed March 19, 1887. Serial No. 231,618. (No model.)

To all whom it may concern:

Be it known that I, RICHARD LUKINS, of Randolph, in the county of Cedar and State of Nebraska, have invented a new and useful Improvement in Car-Pushers, of which the following is a specification.

My invention is an improved car pusher or mover; and it consists in certain features of construction and novel combinations of parts, as will be hereinafter described and claimed.

In the drawings, Figures 1 and 2 are side views of the device, showing the parts thereof in different positions; and Fig. 3 is a top plan view of the device.

The base A is provided with depending guides D, which in practice project down along the opposite sides of the rail and serve to guide the device as it is moved along the rail to the car-wheel. These guides are preferably the extended lower ends of standards d d', which are shown as arranged near the opposite ends of the base.

To the standards d, which form an upright and provide a support therefor, I pivot the pinch-bar E, which has an extension, at e, in front of the upright d d', which extension forms the point of the pinch-bar, and in practice impinges the periphery of the car-wheel. At its rear end the pinch-bar is pivoted to the handle-lever F, the forward end of which is pivoted to and fulcrumed on a link or links, C, which are pivotally connected with the base, usually as shown, through the intervention of the standards d d'.

It will be noticed that the connection of the pinch-bar with the lever is in rear of the pivoted connection of the said lever with its swinging fulcrum C, so that the downward movement of the lever serves to give the op-

erative movement to the pinch-bar, enabling 40 the application of great force to the desired end.

The invention is very simple, and the device in practice will be found to develop great power, and thus efficiently serve the purpose 45 for which it is designed.

Having thus described my invention, what I claim, and desire to secure by Letters Patent, is—

1. A car-pusher comprising a base having 50 guides whereby to direct its movement on a rail, a pivoted pinch-bar, a lever, a swinging fulcrum, to which said lever is pivoted, and connections, substantially as described, the pinch-bar being pivoted to the lever at a point 55 in rear of the pivot or fulcrum of such lever, substantially as described, and for the purpose specified.

2. The combination of the base having depending guides whereby to direct its movements along a rail, a pivoted pinch-bar having an extension in advance of its pivot, a support on which such bar is pivoted, a swinging fulcrum, and a lever pivoted to said fulcrum, and having the pinch-bar pivoted to it in rear 65 of the point where it is pivoted to the swinging fulcrum, substantially as set forth.

3. The herein-described car-pusher, consisting of the base, the uprights d d', having extensions D D, forming guides, the pinch-bar 70 E, having extension e, the hand-lever F, and the link C, substantially as described, and for the purposes specified.

RICHARD LUKINS.
